SLED FOR TRANSPORTING A SEISMIC ENERGY GENERATOR

Clifford D. Dransfield, Dallas, Tex., assignor to Atlantic Richfield Company, Los Angeles, Calif.

Filed Jan. 3, 1974, Ser. No. 430,545

Term of patent 14 years

Int. Cl. D12—14

U.S. Cl. D12—1

FIG. 1

FIG. 2

FIG. 3

FIG. 4

FIG. 1 is a side elevational view of a sled for transporting a seismic energy generator embodying my design, the opposite side being a mirror image thereof;

FIG. 2 is a top plan view thereof;

FIG. 3 is a front elevation view thereof; and

FIG. 4 is a rear elevational view thereof.

I claim:

The ornamental design for a sled for transporting a seismic energy generator, as shown.
